UNITED STATES PATENT OFFICE.

JOHN GUNNING, OF PHILADELPHIA, PENNSYLVANIA.

LAMP-CHIMNEY PROTECTOR.

SPECIFICATION forming part of Letters Patent No. 551,859, dated December 24, 1895.

Application filed April 3, 1895. Serial No. 544,225. (No model.)

To all whom it may concern:

Be it known that I, JOHN GUNNING, a citizen of the United States, residing at the city of Philadelphia, in the county of Philadelphia 5 and State of Pennsylvania, have invented certain new and useful Improvements in Lamp-Chimney Protectors, of which the following is a specification.

The principal objects of my invention are, 10 first, to provide an efficient, simple, durable and comparatively inexpensive device adapted to meet requirements and perform the functions of a lamp-chimney protector; second, to provide a lamp-chimney protector with 15 a frame, support or body of copper or other metallic substance or material and a slab, disk, plate or wrapping of asbestos or other heat-non-conducting material held in or on said frame and adapted to occupy a position 20 within the chimney above the flame; and, third, to provide a lamp-chimney protector 25 consisting of a blank of copper or other suitable metallic substance stamped into required shape or form to receive the asbestos and provided with arms adapted to rest on the top 30 of the chimney and to support the asbestos above the gas, oil or other flame.

My invention consists of a lamp-chimney 35 protector constructed and arranged in substantially the manner hereinafter described and claimed.

The nature, characteristic features, and 40 scope of my invention will be more fully understood from the following description, taken in connection with the accompanying drawings, 45 forming part hereof, and in which—

Figure 1 is a front elevational view of a 50 lamp-chimney, illustrating a protector embodying features of my invention suspended 40 within the chimney from the top rim thereof. Fig. 2 is a perspective view, enlarged, of the 55 protector illustrated in Fig. 1, the frame or body thereof consisting of a piece of wire coiled and covered with asbestos or other heat- 60 non-conducting material. Fig. 3 is a top or plan view of the supporting wire frame or body flattened out for the reception of the heat-non-conducting material constituting the 65 protector of Fig. 2. Fig. 4 is an enlarged 70 perspective view of a modified form of the 75 protector, illustrating a metal strip or blank covered with asbestos held in place by a cop-

per strip or band and rivet. Fig. 5 is a top or plan view of a blank flattened out, forming the supporting frame or body of the protector 55 illustrated in Fig. 4. Fig. 6 is a perspective view of a further modified form of the protector in which a slab of asbestos or other heat- 60 non-conducting material is held in a flame and is supported by a blank provided with retaining and supporting arms; and Fig. 7 is a top or plan view of the blank flattened out, constituting the frame or body of the protector 65 illustrated in Fig. 6.

Referring to the drawings, *a* represents the 70 lamp-chimney, and *b* the upper rim or edge thereof. From this rim or edge *b* are suspended the metallic arms *c* and *c'*, bent respectively at *d* and *d'* to fit around the rim or edge *b* of the chimney *a*. The arms *c* and *c'* 75 project downwardly within the chimney *a* and terminate in a body, frame or base *e* of metal, onto which asbestos or other heat-non-conducting material *f* is mounted or supported.

In the form illustrated in Figs. 1, 2, and 3 75 the frame, body, or base *e* and the arms *c* and *c'* are formed of a single piece of wire, preferably copper, bent and coiled as illustrated in Fig. 3 of the drawings. Around the coiled portion or frame *e* is wrapped asbestos or 80 other non-conducting material *f*, which is held in place by a strip or band *g* of metal, preferably copper, secured thereto by means of a rivet *h*, passing through the strip *g*, the asbestos *f*, and the opening *i* in the body or 85 frame *e*, substantially in the manner illustrated in Fig. 2 of the drawings.

In the modification illustrated in Figs. 4 and 5 the arms *c* and *c'* are integral with the metal body or frame *e'*, the arms and body 90 or frame being stamped or sheared out of sheet metal, preferably copper, because, as practice has demonstrated, this metal is adapted to withstand a high heat without melting or fusing; and, moreover, a protector 95 such as described and constructed as explained is especially adapted for the chimney of the Welsbach type of lamp, in which the flame thereof is brought to a high state of incandescence and without fear of breaking 100 the chimney, while the device of my invention is suspended therein above the inflamed mantle of such lamp. This is due to the fact that the more or less intense heat arising

from the flame of the lamp is attracted toward the center thereof to the said body, thereby allowing the products of combustion or heat arising from the flame of the lamp to escape around and through the passage-way formed between the said body and wall of the chimney in volume from the top thereof unobstructed in any manner, thus greatly lessening the tendency to breakage of the chimney. It may be here remarked that the cooler portion of the chimney is next to the wall thereof and the hotter portion about the said body, whereby effective working, as extended practice has demonstrated, is insured. In the above form of the device the asbestos or similar substance is wrapped around the frame or body e' and secured thereon by a copper strip or band g , riveted thereto in a similar manner as illustrated in Fig. 2, the rivet h passing through a central opening i in the frame or body e' of the metal blank.

In the modification illustrated in Figs. 6 and 7 the frame or body e^2 and arms c and c' are integral, being stamped out of sheet metal, preferably copper. In this form the frame e^2 is provided with preferably four prongs or fingers k , and the asbestos is to be placed on the under face of the frame e^2 and lapped around into the upper face and retained therein by bending down the series of prongs or fingers k upon the asbestos and introducing the rivet h through the free end portion of the series of fingers and the body of the frame e^2 , as illustrated in Fig. 6.

In operation the protector is suspended by the arms c and c' from the upper edge or rim b of the chimney a . The frame or body, with its asbestos covering, disk or plate b , is sus-

pended within the chimney a , directly over or above the flame.

It is here remarked that it is preferred to make the arms and frame or body of the protector of copper, as that metal will sustain a much greater heat before melting or fusing than most other metals that have been experimented with for the purpose of my invention. Instead of copper, however, soft steel or other metal capable of sustaining an intense heat without melting may be used without departing from the spirit of my invention.

Having thus described the nature and objects of my invention, what I claim as new, and desire to secure by Letters Patent, is—

1. A lamp chimney protector, consisting of a blank having integral supporting arms bent upward and outward and terminating in downwardly projecting clips, heat non-conducting material applied to said blank and banded thereto and secured by a rivet, substantially as described.

2. A lamp chimney protector, consisting of a blank having integral supporting arms bent upward and outward and terminating in downwardly projecting clips, said blank also provided with fingers or prongs for retaining asbestos or the like in connection with said blank and secured by means of a rivet, substantially as described.

In testimony whereof I have hereunto set my signature in the presence of two subscribing witnesses.

JOHN GUNNING.
